Stanley Sosnoskey INVENTOR
BY *Victor J. Evans*

ATTORNEY

UNITED STATES PATENT OFFICE.

STANLEY SOSNOSKEY, OF PHOENIXVILLE, PENNSYLVANIA.

SWITCHMAN'S ROD.

Application filed June 2, 1922, Serial No. 565,475. Renewed March 8, 1923.

To all whom it may concern:

Be it known that I, STANLEY SOSNOSKEY, a citizen of the United States, residing at Phoenixville, in the county of Chester and State of Pennsylvania, have invented new and useful Improvements in Switchmen's Rods, of which the following is a specification.

This invention comprehends the provision of a switch operating rod constructed to prevent the user from receiving shocks incident to the use of the rod, or in other words, when brought into contact with the rail of the track.

More specifically stated, the invention contemplates the provision of a rod of this character which is made up of two sections which are spaced apart, but suitably connected together by a casing of insulated material for the purpose specified.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views, and wherein:

Figure 1 is a view of the rod in elevation.

Figure 2 is a sectional view taken on line 2—2 of Figure 1.

Figure 3 is a sectional view taken on line 3—3 of Figure 1.

Figure 4 is a detail view of one of the sleeve-like members.

Referring to the drawing in detail, 10 and 11 indicate the respective sections of the rod which are spaced apart but arranged in axial alinement, and each section is received by one of the sleeve-like members of the character illustrated in Figure 4. Each of these members is indicated at 12, and is formed at one end to provide a flange 13. Each rod section is threaded for a portion of its length, and associated with each section is a lock nut 14,

the latter bearing against the adjacent ends of the sleeve-like members 12. These sleeve-like members are joined or coupled together by means of a casing 15 which may be constructed from any suitable insulated material the casing being attached to the sleeve-like members and the flanges 13 thereof.

Consequently, by reason of the construction shown, the current from the rail cannot be transmitted through the rod to the hand of the user, incident to the use of the rod for throwing the switch. It is to be understood that the device in its entirety may vary in size, and that the component parts of the device constructed of any suitable material without departing from the spirit of the invention.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. A switchman's rod comprising spaced sleeve-like members, each of said members being closed at one end, said members being disposed in spaced axial relation, a rod section fitted in each sleeve-like member, a lock nut associated with each rod section and a casing of insulated material connecting said sleeve-like members as for the purpose specified.

2. A switchman's rod comprising spaced sleeve-like members, said members being spaced and disposed in axial relation, a rod section fitted in each sleeve-like member, a lock nut associated with each rod section, a casing of insulating material connecting said sleeve like member, and insulating members arranged within the casings and interposed between the adjacent ends of said sleeve-like members.

In testimony whereof I affix my signature.

STANLEY SOSNOSKEY.
